APPARATUS FOR THE TREATMENT OF TEXTILES

Albert Mellor and Robert Martin, Spondon, near Derby, England, assignors to Celanese Corporation of America, a corporation of Delaware

Application May 12, 1942, Serial No. 442,618
In Great Britain June 18, 1941

1 Claim. (Cl. 68—158)

This invention relates to an apparatus and process for the liquid treatment, in continuous manner, of textile fabrics in open width and is concerned particularly with an apparatus which can be used to effect such treatments while the fabric is under very little or substantially no tension.

Certain fabrics, notably those comprising yarns of cellulose acetate or other cellulose ester or ether, cannot in general be safely dyed or otherwise processed in rope or other folded form, e. g. on a winch, without a previous liquid treatment in open width during which the fabric is thoroughly wetted out and any strains are released. In the absence of such a pretreatment the fabric is prone to acquire permanent creases or "river marks" during the treatment in folded form.

Again it is often desirable to effect the liquid treatment of textile fabrics whilst allowing free shrinkage in all directions to take place. An example of such a treatment is the development of the figure on crepe fabrics. A fabric is woven which has in the weft, or both the weft and warp, highly twisted yarns, for example yarns of natural silk or of regenerated cellulose artificial silk or of cellulose acetate. Usually the fabric is then subjected to hot aqueous treatment, for example at temperatures of 85-90° C. or higher, for the purpose of developing the crepe figure. It is essential that during this treatment the fabric shall be substantially free to shrink both in the weft direction and in the warp direction if full development of the crepe figure is to be attained. Moreover, especially in the case of cellulose acetate fabrics, owing to the plasticity of the yarn at the temperature employed, there is considerable risk of uneven or incomplete crepe development and of permanent creasing and distortion.

It will be appreciated therefore that most of the machines commonly used for the liquid treatment of textiles are unsuitable when effecting crepe development of cellulose acetate materials. For example, the use of the jig involves some application of tension to the material and does not permit free shrinkage. Again, use of a winch machine involves both creasing of the material and some tension and machines of the type in which the fabric is suspended by the selvedge or in loops or is suspended as a hank are costly as regards labor requirements and do not permit continuous operation.

In accordance with the present invention an apparatus for the liquid treatment of textile fabrics in continuous manner while in open width comprises a vat for the liquid, means for feeding

the fabric into the vat, a member capable of presenting a moving surface which can guide the fabric down into and below liquid in the vat, means for withdrawing the fabric from the liquid, and means for adjusting the relative rates of operation of the said fabric feeding means and member capable of presenting a moving surface on the one hand and the fabric-withdrawing means on the other, so as to compensate for shrinkage of the fabric in the liquid.

The device capable of presenting a moving surface is most conveniently in the form of a drum rotatable about a horizontal axis with a part only of its periphery immersed in liquid in the vat. Preferably the drum is of large diameter, for example at least 3 feet e. g. 5 to 9 feet or more. A drum of 6 to 8 feet diameter is very suitable. Advantageously it is of skeleton construction having a periphery through which liquid can pass readily, for example a periphery of perforated metal sheet. Preferably the periphery is covered with a textile material, for example woven or knitted cotton material e. g. madapolam.

It is convenient to have means for bunching the textile fabric undergoing treatment into rope form after it leaves the liquid in the vat. This can take the form of an eye e. g. of porcelain, through which the fabric is drawn. In such case the fabric-withdrawing means is conveniently in the form of a winch, for example an elliptical winch. Means can be provided for spraying liquid on the fabric as it leaves the bath. This is advantageously placed immediately above the eye or other means for bunching the fabric into a rope when such device is incorporated. Preferably an infinitely variable gear is used to permit adjustment of the relative rates of fabric feed to and withdrawal of fabric from the vat. Conveniently a common shaft is used to drive both the fabric feeding device and the fabric withdrawing device, the infinitely variable gear being included in the drive to the latter from the shaft.

The invention will now be described with reference to the accompanying drawing which shows one form of apparatus according to the invention. Fig. 1 shows a diagrammatic side elevation of the apparatus with the side wall omitted. A drum 1 rotatable about a horizontal axle 2 is mounted so that nearly half is within a vat 3 to contain the treatment liquid which can be heated by steam supplied through pipes 8. A pair of driven rollers 4, 5 serve to draw fabric from a roll 6 by way of the idler roller 7 and deliver it into the vat 3 so that it meets the drum 1 at about the point where the periphery of the latter

enters the liquid in the vat. The general path of the fabric through the apparatus is indicated by the dot-and-dash line 8. An elliptical winch 10 serves to draw fabric from the vat 3 via the porcelain eye 11. Idler rollers 12, 13 are provided within the vat 3 to guide the fabric through the vat between the drum 1 and the point at which it is withdrawn from the vat. If desired a horizontal screen of perforated metal sheet or the like can be fitted just above the steam pipes 9 to prevent the fabric from touching the said pipes. A spray nozzle 44 is provided through which liquid can be sprayed over fabric being withdrawn from the vat 3 through the eye 11.

The vat 3 can be provided with a cover 14 to 15 reduce heat losses and escape of steam.

The driving of the various parts of the apparatus is effected by an electric motor 15 which, by a belt 16 and pulleys 17 and 18 drives a train of gears (not shown) carried on shafts 19, 20, 21 20 and 2 the latter being the axle of the drum 1. A pulley 22 on shaft 21 drives the fabric feed rollers 4, 5 by way of the pulley 24, the chain 25 and the chain sprockets 26, 27, 28, 29. A second pulley 30 on shaft 21 drives the winch 10 through an infinitely variable gear box 31 of which the hand-wheel for controlling the gear ratio is indicated at 32. The drive from pulley 30 to the gear box is by the belt 33 and the pulley 34. The drive from the gear box 31 to the winch 10 is by way 30 of the pulley 35, the belt 36, the countershaft and pulleys 37, 38, 39, the belt 40 and the pulley 41.

The periphery of the drum 1 is made of perforated sheet metal covered with textile fabric 35 as illustrated in Fig. 2 in which is shown the sheet metal 41, holes 42, and covering of textile fabric 43, the latter being broken away at the right hand side of the figure to show the holes 42 more clearly.

Various modifications of the above described apparatus are within the scope of the invention. For example, instead of the drum 1 an endless driven belt having, beneath the liquid, a path generally similar to that of the drum, may be employed. Again, instead of the non-contacting rollers 4, 5, a pair of driven nip rollers can be used. Moreover a type of winch different from that of the elliptical winch illustrated, for example a circular winch can be employed. Further, the steam used for heating liquid in the vat can either be admitted directly into the liquid (i. e. from "open" steam pipes) or can be passed through a series of pipes in the liquid without direct contact with the liquid. It is often convenient to fit both types of steam heating, open steam pipes for heating the liquid rapidly to the working temperature, and closed steam pipes for maintaining the temperature subsequently so that during working the liquid is not progressively 60 diluted by condensed steam used for heating.

As indicated above, an infinitely variable gear device can be used to permit control of the relative rates of introduction of the fabric into and withdrawal from the vat 3. Other devices can be used for this purpose, for example, mechanically independent drives to the fabric-feeding device and the fabric-withdrawing device respectively. For instance separate electric motors, of which at least one is of an adjustable speed type, 70

can be employed for the respective drives. If desired the relative speed of the fabric-feeding and fabric-withdrawing devices may be controlled by a device responsive to tension in the fabric so that the latter is automatically maintained substantially free from tension or under some small predetermined tension during its treatment in the apparatus.

As stated above the general path through the apparatus of a fabric undergoing treatment is indicated by the dot-and-dash line 8. Usually it is advantageous to deliver the fabric upon the surface of the drum 1 at a point just before it enters the liquid in the vat.

The spray nozzle 44 can be used to spray cooling or washing liquid on to the fabric as the latter leaves the vat.

The new apparatus is particularly useful for subjecting fabrics containing highly twisted yarns, and especially fabrics containing highly twisted yarns of cellulose acetate or other cellulose ester or ether, to hot aqueous treatments for the purpose of developing crepe figures thereon. Such processes only operate satisfactorily if the fabric is substantially free to shrink during the hot aqueous treatment. Such free shrinkage is readily permitted when the hot aqueous treatment is carried out with the aid of the apparatus of the invention.

When treating cellulose acetate or other cellulose ester or ether fabrics it is usually advantageous to spray the fabric with cold water as the fabric is withdrawn from the hot liquid. This is especially the case when the fabric is bunched together in rope form as it is withdrawn.

Having described our invention what we desire to secure by Letters Patent is:

Apparatus for the liquid treatment of textile fabrics in continuous manner while in open width 40 and which permits free shrinkage thereof, which comprises a vat for the liquid, a drum rotatable about a horizontal axis with part only of its periphery immersed in liquid in the vat, said drum periphery consisting of perforated metal sheet 45 covered with textile fabric, driven rollers for feeding the fabric into the vat so that the fabric meets the drum at about the point where the periphery of the latter enters the liquid in the vat and is guided down into liquid in the vat and beneath the drum by the moving periphery of the drum, a winch for withdrawing the fabric from the liquid 50 at the opposite side of the drum to that at which the fabric enters the liquid, an eye through which the fabric can be passed and thereby bunched together into a rope after leaving the liquid and prior to reaching the winch, and means for spraying liquid on to the fabric after the latter leaves the liquid in the vat and before it reaches the winch, the drum, the rollers and the winch being driven from a common shaft, and the drive of the winch including an infinitely variable gear, the construction and arrangement being such that the relative rates of operation of the fabric feeding and withdrawing means maintain the fabric 55 in relatively smooth, unfolded condition in the vat while compensating for shrinkage of the fabric in the liquid.

ALBERT MELLOR.
ROBERT MARTIN.
